UNITED STATES PATENT OFFICE.

HENRY M. MELTON, OF HOUSTON, TEXAS.

SEAL.

Application filed November 10, 1924. Serial No. 748,888.

To all whom it may concern:

Be it known that I, HENRY M. MELTON, a citizen of the United States, residing at Houston, in the county of Harris and State of Texas, have invented certain new and useful Improvements in a Seal, of which the following is a specification.

This invention relates to new and useful improvements in a seal.

10 One object of the invention is to provide a seal of the character described specially designed for use in sealing railway freight car doors.

It is common practice, in shipping freight 15 to seal the freight car doors, after the car has been loaded at the point of origin, to prevent interference with, or theft of, the shipment in transit. This is usually accomplished by means of a tie, or loop, of tin or 20 similar metal in the form of a metallic strip, which ties together the interlocking parts of the door latch, and whose free ends are secured together by means of a soft metal rivet. The ends of the tie are riveted together 25 by means of a seal, which is designed not only to overturn, or upset, the tail of the rivet, but also to form an impression thereon, providing data to indicate the line over which the shipment moves, as well as the 30 point of origin of the shipment.

In application the loop of the tie is fitted through the parts of the latch of the door to be secured and the rivet is then fitted in place through holes in the free ends of the 35 tie and riveted securely in place. In order to obtain a perfect impression, and to securely fasten the ends of the tie together, it is essential that the free ends of the tie and the rivet be fully inserted, in proper position, into the seal before the sealing operation takes place, and it is further necessary that said free ends of the tie be firmly held together while the tail of the rivet is being upset, as otherwise an imperfect impression 45 will be made on the rivet and the ends of the tie will often be broken in the upsetting operation. It is the prime object of this invention to provide a seal which cannot be operated until the ends of the tie, to be secured, 50 are properly and fully inserted into the seal, and which, in operation will securely hold the ends of the tie together during the operation of the seal.

Another object of the invention is to pro-

vide a seal of the character described which 55 is of very simple construction and consequently may be very cheaply produced, and which is effective in operation.

With the above and other objects in view 60 this invention has particular relation to certain novel features of construction, operation and arrangement of parts an example of which is given in this specification and illustrated in the accompanying drawings, 65 wherein:—

Figure 1 shows a side view of the seal, partly in section.

Figure 2 shows a cross sectional view taken on the line 2—2 of Figure 1.

Figure 3 shows a fragmentary end view 70 thereof, and

Figure 4 shows an edge view of the tie employed.

Referring now more particularly to the drawings, wherein like numerals of reference designate similar parts in each of the figures, the numeral 1 designates the head of the seal, which has a deep slot 2 in one edge, forming the spaced side flanges 3, 3, which have extended ears 4, 4 and 5, 5, provided 75 with aligned bearings. The grip handles 6 and 7 are pivoted between these respective ears, by means of the bearing pins 8 and 9. These pins are fitted through the corresponding handles and work in the aligned 80 bearings of the adjacent ears. The handle 6 is extended into the slot 2 forming a die block 10. Interposed between the die block 10 and the opposing part of the head 1 there is a comparatively strong coil spring 11, 90 whose ends are retained in shallow sockets formed, in said block and head, respectively. This spring tends to hold the seal in open position.

The opposing faces of the head 1 and the 95 block 10 have the confronting dies 12 and 13 formed therein, having certain characters formed therein, for indicating the railway line, and the particular station thereon, respectively, where the car was sealed.

It is to be noted that the outer ends of the flanges 3 are flush with the corresponding outer end of the head. This formation makes it impossible to insert the free ends of the tie into the seal from the side of the seal, and insures the uniform insertion of the tie ends into the seal, to the end that the impressions on the rivets of the ties will 105

be in uniform position so that the data may be the more easily read by inspectors.

There is a latch 14, pivoted at one end to the die block 10, and whose other end works in the aligned bore 15, of the head.

This latch is formed with a shoulder 16 which normally engages the head to lock the seal against operation. A flat spring 17 is secured at one end, to the head, and its other end presses against said latch underneath. When the tie is fully inserted in the seal the ends of the tie disengage said latch which permits the operation of the seal but the latch prevents such operation until the free ends of the tie are fully inserted to align the rivet with the dies 12 and 13. A perfect impression is thus insured. When the seal is operated the latch works in the bore 15, but when the seal is again opened the latch is operated into locking position by the spring 17, to prevent the premature operation of the seal.

The inner side of the handle 7, at its pivoted end, has two cams, 18 and 19, the former of which works in a deep slot 20 in the outer side of the block 10 and the latter of which works against the outer side of said block. There is a plunger 21 which works in a transverse bore 22 in the outer end of the block 10 and is seated on a yieldable seat 23. The inner end of the plunger works against the cam 18 and its outer end projects out through a suitable bearing through the operative face of the die block 10.

In operation the loop, or tie 24, is inserted through the parts of the car door latch, to be secured, and the rivet 25 is then passed through the holes, provided for it, in the free ends of the tie, as shown in Figure 4. The free ends of the tie are then inserted, endwise into the slot 2 between the head and die block 10 until the said free ends disengage the latch 14, at which time the rivet head is in position to seat fully against the die 12. The handles 6 and 7 are now gripped together. As the handle 7 moves toward the handle 6 the cam 18 first operates to project the plunger 21 out against the tie 24 to press its sides firmly together and thereafter the cam 19 comes into contact with the opposing side of the die block 10 and forces said block toward the opposing face of the head forming the bottom of the slot 2. This block moves relative to the plunger 21, causing the plunger to recede, relative to the block, but to remain stationary, relative to the tie. As the handles are forced further together the tail of the rivet is upset by the die 13, as indicated in dotted lines in Figure 4, and the desired impression is made thereon, the final step, of the operation, however, being accomplished by the handle 7, acting through the elevated fulcrum 26, on the handle 6, and effecting a final thrust of the die block 10 against the rivet.

The plunger 21, during the sealing operation, operates, as above stated, to hold the sides of the tie closely together and thus prevents the rivet from bulging between the free ends of the tie and bursting, or breaking one or both of said ends.

When the handles, or one of them are released the springs 11 and 23 operate to carry all the parts back to original position for the next operation.

The handle 6 is provided with a ring 27 for convenience in handling the seal.

Only one form of the plunger 21, for the purpose stated, has been shown, but it is obvious that this element is capable of various formations and other means than that shown may be devised for its successful operation. It is of course, obvious that various other mechanical changes in structure and design may be made, without departing from the scope of the appended claims.

What I claim is:—

1. A seal including a slotted head, a pair of handles pivoted in the slot of the head, one of said handles being formed into a die block in said slot, a pair of cams formed on the other handle within said slot, a plunger mounted in said block, one of said cams being disposed to operate the plunger and the other cam being adapted to actuate the block relative to the head.

2. A seal including a head formed with a slot, a pair of handles whose adjacent ends are pivoted in said slot, one of said handles being formed into a die block in the slot, a plunger in said block, a pair of cams on the adjacent end of the other handle, one of said cams being disposed to actuate said plunger and the other cam being adapted to actuate said block when said handles are relatively moved.

3. A tie seal including a head having spaced side flanges whose ends are flush with the end of the head, a handle pivoted thereto one end of which is formed into a die block, a yieldable member interposed between said head and block, and normally holding them spaced apart, a releasable latch normally locking said block and head in said spaced relation, said latch being adapted to be released by the tie when inserted in the die, and means connected to the head for actuating the head and block toward each other when said latch is released.

4. A seal formed with two die members pivoted together but spaced apart to permit the insertion of a tie between them, means limiting the tie to endwise insertion between the members, means for locking said members in spaced relation, said means being adapted to be released through said tie when so inserted, means for actuating said members to clamp said tie, and means adapted

to impinge against, and clamp said tie, in advance of said actuation of the die members.

5. A seal formed with two die members pivoted together, means normally locking said members in spaced relation to form a tie receiving slot between them, spaced side members adapted to limit the tie to endwise insertion in the slot, said means being re-
10 leasable through the instrumentality of a tie inserted between said members, a plunger mounted in one member, means for actuating said plunger and said members through which the plunger and die members will
15 clamp the tie in succession, said actuating means including a handle and cams thereon.

6. A seal formed with two die members pivoted together, a handle forming a grip

carried by one of said die members an actuating handle, forming a grip, pivoted 20 to the other member, means normally holding said members apart to form a tie receiving space between them, a tie clamping device movably mounted in one of said members, means carried by the actuating handle 25 and adapted to actuate said members into clamping relation with the tie, means carried by the actuating handle and adapted to actuate the clamping device into clamping relation with the tie in advance of the 30 actuation of said members, and to hold said device in such relation during the operation of said members.

In testimony whereof I have signed my name to this specification.

HENRY M. MELTON.
